Primary Examiner — John R Yeh(74) *Attorney, Agent, or Firm* — Wayne & Ken, LLC;
Tony Hom(57) **CLAIM**

The ornamental design for a mop cloth, as shown and described.

DESCRIPTION

FIG. 1 is a front elevation view of a mop cloth showing my new design;

FIG. 2 is a back elevation view thereof;

FIG. 3 is a left side view thereof, the right side view being a mirror image thereof; and,

FIG. 4 is a top plan view thereof, the bottom plan view being a mirror image thereof.

The broken lines in the figures illustrate portions of the mop cloth that form no part of the claimed design.

1 Claim, 4 Drawing Sheets---
